YUSKE MIYASAKI, OF MCKEES ROCKS, PENNSYLVANIA.

CAST TRUCK-BOLSTER.

1,156,305.

Specification of Letters Patent. Patented Oct. 12, 1915.

Application filed February 15, 1915. Serial No. 8,267.

To all whom it may concern:

Be it known that I, YUSKE MIYASAKI, a subject of the Emperor of Japan, residing at McKees Rocks, in the county of Allegheny and State of Pennsylvania, have invented certain new and useful Improvements in Cast Truck-Bolster's, of which the following is a specification, reference being had to the accompanying drawings.

10 This invention relates to cast truck bolsters, and is more particularly designed as an improvement upon the bolster shown in my prior Patent, No. 1,091,375, issued March 24, 1914.

15 The present invention has for its primary object to provide a cast truck bolster which is of such construction that maximum strength may be obtained with the use of a minimum quantity of metal.

20 It is an additional object of the invention to provide a bolster which will offer the greatest resistance to vertical and horizontal strains, by maintaining the thickness of the various parts of the bolster nearly uniform, 25 such uniformity in thickness reducing liability of latent defects in the casting of the bolster to a minimum.

The invention has for a further object to 30 provide a cast truck bolster wherein the usual vertical longitudinally extending web is eliminated, but without reducing the strength of the bolster.

It is still another object of the invention 35 to provide a cast truck bolster embodying integrally connected spaced pairs of longitudinal chords the top plate or chord being provided upon its longitudinal edges with depending flanges, whereby a maximum resistance in the bolster construction 40 to horizontal strains, is obtained.

The invention has for a further object to produce a cast bolster having an improved central body construction wherein the central bearing plate is effectively reinforced, 45 and difficulties which are usually encountered in the coring of the bolster body minimized.

With the above and other objects in view, 50 my invention consists in the novel features of construction, combination, and arrangement of parts to be hereinafter more fully described, claimed, and illustrated in the accompanying drawing, in which,

55 Figure 1 is a top plan view of a cast car bolster constructed in accordance with the present invention; Fig. 2 is a side elevation

thereof; Fig. 3 is a central vertical section taken on the line 3—3 of Fig. 1; and Fig. 4 is a section taken on the line 4—4 of Fig. 2.

Referring in detail to the drawing, 5 and 6 designate the two longitudinally extending top chord members of the bolster, which are integrally connected at intervals by a central longitudinally extending web 7 and the spaced braces 8 which are integrally formed with the opposite faces of said web and the opposed faces of the chord members 5 and 6.

9 and 10 designate the upper and lower bottom chord members which are also integrally connected to each other in spaced relation in a similar manner to the chord members 5 and 6. The lower chord 6 of the upper pair is of appreciably less width than the uppermost chord member or compression plate 5 and gradually tapers from the center of the bolster to the ends of said chord member 6, at which points, it is integrally connected to the opposite ends of the lower chord member 9, as shown at 11.

At their opposite ends, the top and bottom chord members 5 and 10 are integrally connected together by the vertical walls 12. The outer faces of these vertical walls have the usual beam engaging ribs 13 formed thereon and the extended ends of the upper chord member 5 are provided with bearings 14 and spring seats 15, in the usual manner.

The upper and lower pairs of longitudinally extending chord members are integrally connected and braced to resist vertical strains, by a central tubular truss 16. The compression plate or top chord member 5 is centrally formed with an upwardly projecting tubular boss 17 to receive the center pin, and a concentrically related upstanding flange 18 is also formed upon said compression plate. The diameter of this flange is preferably, although not necessarily, equal to the maximum width of the compression plate 5, while the vertical cylindrical truss 16 is of somewhat less diameter, although it is within the contemplated

105 purpose of the invention to also make this truss of a diameter equal to the compression plate 5. The central portion of the compression plate is effectively reinforced by means of a plurality of longitudinally extending bracing webs 19 which integrally connect the bottom face of said compression plate with the vertical wall of the

tubular truss 16. This central tubular truss is cast integrally at its ends with the upper and lower longitudinal chord members 5 and 10, while the chord members 6 and 9, 5 at the center of the bolster, merge into and form an integral part of the wall of said truss. By the provision of the annular up-standing flange 18 which extends across the entire width of the compression plate 5, the 10 bearing portion of said plate is effectively reinforced, and by providing a central truss of the same diameter through its length, and without a taper, the proper coring of the same is greatly expedited. The bearing 15 area of the vertical truss upon the bottom chord members is also increased. The coring of the truss is further simplified by extending the bracing flanges 19 longitudinally of the bolster instead of radially.

20 It will be noted, from the above description, that the usual vertical longitudinally extending web between the upper and lower chord members of the bolster is eliminated. The metal which would be used in the pro- 25 vision of such webs is employed in increasing the width and thickness of the upper and lower pairs of chord members, so that the thickness of said members will be more nearly equal to the thickness of the other 30 parts of the bolster construction. In this connection, it will be noted that the upper longitudinally extending chord member or compression plate 5 is of the greatest width, and the longitudinal edges of this compres- 35 sion plate 5 have depending flanges 20 formed thereon, the ends of said flanges being integral with the vertical side walls 12 of the bolster. These flanges 20 preferably extend downwardly for a short distance be- 40 low the plane of the bottom face of the longitudinal chord member 6, said flanges being spaced from the central cylindrical truss 16 but connected to said truss by the integral bracing webs 21. By providing the chord 45 members 6 and 9 without the longitudinally extending connecting web, greater section-modulus is obtained both vertically and horizontally of the bolster, from the use of an equal amount of metal. In a bolster having 50 the central longitudinally extending web, said web is, to a great extent, close to the neutral axis of the bolster and is less effective in obtaining a maximum section-modulus than is the case when the same 55 amount of metal to be used in such a web, is concentrated in the chord members 6 and 9, at a remote distance from the neutral axis, as shown in the accompanying drawing. If 60 the metal heretofore used in forming the central web in the bolster is used in forming the chord members 5 and 10, the width of which is limited, the strength of the bolster or its resistance to vertical strains, will be increased; but there will also be greater 65 liability of latent defects in the casting of

the bolster, and more particularly in these chord members which are of greater thickness than the other parts of the bolster. In order to avoid this and also obtain greater resistance to horizontal pressures and bending strains, the flanges 20, above referred to, are formed on the upper chord member 5. These flanges are more effective in increasing the section-modulus of the bolster horizontally than any other parts thereof and 70 with the use of a relatively small amount of metal. An increase in the width of the flanges 20 beyond that necessary to produce the desired strength in the horizontal plane of the bolster in order that greater vertical 75 strength may be obtained, is less economical than the increase in the thickness of the metal in the chord members 6 and 9, as the additional quantity of metal in the flanges 20 will be much nearer to the neutral axis 80 than the metal in the members 6 and 9. The increase in thickness of the flanges 20 for the purpose of obtaining greater vertical strength, also increases liability of latent defects in the casting of the bolster at the 85 junctures between the several parts thereof. Therefore, by the provision of the chord members 6 and 9, in combination with the longitudinal flanges 20 on the chord member 90 or compression plate 5, a most economical 95 construction is obtained and one which will offer a maximum resistance to vertical and horizontal strains, whereby the bolster may withstand the bending or buffing stresses to 100 which it is subjected. Such a construction 105 contains greater inherent strength than a bolster having a central vertical longitudinally extending web, by reason of the fact that the thickness of all parts of the bolster is more nearly uniform and it is a generally 110 recognized fact that the most effective means of eliminating defects in the bolster incident to shrinkage strains, is to reduce the difference in thickness of the metal in various 115 parts of the bolster as much as possible.

In order that the requisite strength in 120 bolsters to be employed upon large capacity cars may be obtained, the bottom chord member 10 of such bolster must be increased in width, but such an increase in the width of this chord member is impractical as it would interfere with parts of the truck. In such cases, I, therefore, also form on the longitudinal edges of the chord member 10 the upwardly projecting flanges 22, shown 125 in dotted lines in Fig. 4, said flanges extending slightly above the plane of the upper face of the chord member 9.

From the foregoing description, taken in 130 connection with the accompanying drawing, the manner of construction, as well as the several advantages of my improved truck bolster, will be clearly and fully understood. It will be seen that I have obtained, in a single integral casting, a construction of the

bolster wherein the usual vertical web is eliminated while a maximum of strength and rigidity in the various parts of the bolster is obtained, and the same is enabled to withstand greater stresses than is the case with bolsters of the vertical web type, now in common use. My improved bolster may also be economically manufactured and may be employed upon rolling stock used for various purposes.

It is to be distinctly understood that, in carrying out my invention, changes in the form and proportion of the several parts of the bolster may be necessitated owing to the particular exigencies incident to its use and I, therefore, reserve the privilege of resorting to all such legitimate changes as may be fairly embodied within the spirit and scope of the invention as claimed.

Having thus fully described my invention, what I desire to claim and secure by Letters Patent is:—

1. A cast truck bolster including spaced longitudinally extending parallel chord members, one of said members being provided upon its edges with longitudinally extending flanges projecting beyond the corresponding edges of the other chord member and in opposed relation thereto.

2. A cast truck bolster including spaced parallel longitudinally extending chord members, one of said members having flanges formed on its longitudinal edges extending toward the other chord member and beyond said member in spaced relation to the longitudinal edges thereof.

3. A cast truck bolster consisting of upper and lower pairs of longitudinal chord members integrally connected together at the center of the bolster, the top and bottom chord members being integrally connected to each other at their ends, and separate integral connections between the opposed upper and lower chord members at the ends thereof, the space between the integrally connected ends of the latter chord members and the central vertical truss of the bolster being unobstructed.

4. A cast truck bolster consisting of upper and lower pairs of chord members, a central vertical truss integrally connecting said chord members to each other, the opposed chord members in the upper and lower pairs being integrally connected together at their extremities but unconnected between such terminal connections and the central vertical truss of the bolster, and vertically disposed flanges formed upon the longitudinal edges of one of the upper chord members.

5. A cast truck bolster consisting of upper and lower pairs of longitudinal chord members integrally connected at their ends, a central vertical truss integrally connecting the chord members to each other, the opposed chord members in the upper and

lower pairs being spaced apart to provide unobstructed longitudinally extending openings through the bolster between said vertical truss and the ends of said chord members, and vertically disposed longitudinally extending flanges formed upon the edges of the uppermost chord member.

6. A cast truck bolster consisting of upper and lower pairs of longitudinal chord members integrally connected together at their ends, a hollow vertical truss integrally connecting the chord members to each other at the center of the bolster, the opposed chord members of the upper and lower pairs being spaced apart from their extremities to said central truss to provide longitudinally extending openings in the bolster, and depending flanges formed on the longitudinal edges of the uppermost chord member.

7. A cast truck bolster consisting of upper and lower pairs of longitudinal chord members integrally connected together at their ends, a hollow vertical truss integrally connecting the chord members to each other at the center of the bolster, the opposed chord members of the upper and lower pairs being spaced apart from their extremities to said central truss to provide longitudinally extending openings in the bolster, and depending flanges formed on the longitudinal edges of the uppermost chord member, said flanges extending below the plane of the bottom face of the lower chord member in the upper pair.

8. A cast truck bolster consisting of upper and lower pairs of longitudinal chord members integrally connected together at their ends, a hollow vertical truss integrally connecting the upper and lower chord members together at the center of the bolster, the opposed chord members in the upper and lower pairs being spaced apart between their extremities and said truss to provide longitudinal openings in the bolster, the uppermost chord member being provided with depending flanges on its longitudinal edges, the walls of the truss, said chord members and said flanges being of substantially uniform thickness.

9. A cast truck bolster consisting of upper and lower pairs of longitudinally extending chord members integrally connected together at the opposite ends of the bolster and a hollow vertical truss of uniform diameter throughout its length integrally connecting the chord members at the center of the bolster, and of a diameter approximately equal to the maximum width of the opposed upper and lower chord members.

10. A cast truck bolster consisting of upper and lower pairs of longitudinal chord members, the opposed individual upper and lower chord members being integrally connected together at their ends by vertically extending webs, and a central longitudinal

web extending between the chord members in each pair and beyond said vertical webs to the opposite extremities of the bolster, said latter web connecting the top and bottom chord members together beyond the ends of the other chord member.

11. A cast truck bolster consisting of upper and lower pairs of longitudinal chord members, the members in each pair being integrally connected to each other and the opposed upper and lower chord members being integrally connected together at their extremities, integral connections between the top and bottom chord members at the ends 15 of the bolster, a central hollow vertical truss integrally connecting the upper and lower pairs of chord members, and longitudinally extending flanges formed upon the edges of the top chord member and depending below 20 the plane of the bottom face of the lower chord member in the upper pair.

12. A cast truck bolster consisting of up-

per and lower pairs of longitudinal chord members, the opposed upper and lower members being integrally connected together at 25 their ends, integral connections between the top and bottom chord members at the ends of the bolster, a hollow vertical truss integrally connecting the upper and lower chord members at the center of the bolster, and 30 vertically disposed flanges formed upon the longitudinal edges of the top and bottom chord members, the opposed upper and lower chord members being spaced apart between their integrally connected ends and the central vertical truss to produce longitudinally 35 extending openings in the bolster.

In testimony whereof I hereunto affix my signature in the presence of two witnesses.
